UNITED STATES PATENT OFFICE.

STEPHAN BAADER, OF PHILADELPHIA, PENNSYLVANIA.

REVERSING-GEAR.

1,127,846.

Specification of Letters Patent.

Patented Feb. 3, 1915.

Application filed September 15, 1914. Serial No. 861,756.

To all whom it may concern:

Be it known that I, STEPHAN BAADER, a citizen of the United States, residing at Philadelphia, in the county of Philadelphia and State of Pennsylvania, have invented certain new and useful Improvements in Reversing-Gears, of which the following is a specification.

My invention relates to improvements in reversing gears, the object of the invention being to provide a fluid movable member with a fluid lock normally holding the member against movement, and provide a valve adapted to be manually operated to release the lock and move the member, and adapted to be automatically operated to stop the member and apply the lock.

A further object is to provide a fluid operated mechanism for reversing the gear of a steam engine which can be manually operated with but slight exertion on the part of the operator.

A further object is to provide a fluid operated mechanism for reversing the gears of a steam engine in which a single valve controls the entire operation of the mechanism, said valve manually operated to move the mechanism and automatically operated to stop the movement.

30. A further object is to improve upon the construction disclosed in Patent No. 1,088,255 granted to me February 24, 1914.

With these and other objects in view, the invention consists in certain novel features 35 of construction and combinations and arrangements of parts as will be more fully hereinafter described and pointed out in the claims.

In the accompanying drawings: Figure 1 is a view in side elevation illustrating my improvements. Fig. 2 is an end view of Fig. 1. Fig. 3 is a view in vertical section on the line 3—3 of Fig. 1. Fig. 4 is a view in horizontal section on the line 4—4 of Fig. 3. Fig. 5 is a view in vertical transverse section through the center of my improved valve. Fig. 6 is a top plan view of the valve casing. Fig. 7 is a view in vertical section on the line 7—7 of Fig. 5. Fig. 8 is a view in section on the line 8—8 of Fig. 7. Fig. 9 is a view in vertical section through the valve casing looking in the opposite direction from Fig. 7. Fig. 10 is a face view of the valve member A, and Fig. 11 is a face view of the valve member B.

1 represents a cylinder which is closed at

its ends by heads 2 and 3 respectively, the latter having a stuffing box 4 through which an operating rod 5 projects. This rod is secured to a piston 6 within cylinder 1, and at its outer end is provided with an eye for connection with a link (not shown) of any approved link motion to cause the reverse of the engine as is, commonly understood. The cylinder 1 will be located at any convenient point, adjacent the link motion, and at a point removed from the engine cab, and the movement of the piston 6 will be controlled by air or other fluid as will be hereinafter explained.

8 represents a valve casing which is secured on top of the cylinder 1, and is provided with fluid passages 9 and 10 communicating with passages 11 and 12 respectively in the cylinder 1 connecting the 75 passages 9 and 10 with the respective ends of the cylinder.

The cylinder 1 is provided at one side with a flat plate 15 which may be integral with the cylinder, if desired, and on this plate a guide bracket 16 is fixed. This bracket 16 is provided with guides 17 and 18 for a vertically movable block 19. This block 19 has a recess 20 with its upper and lower walls at an angle to the movement 85 of the block, and in this recess 20 a cam bar 21 is positioned, and is adapted when moved longitudinally to cause the block 19 to move vertically for a purpose which will hereinafter appear. One end of the bar 21 is secured to a clamping yoke 22, and this clamping yoke is fixed to rod 5 and also to a rod 23 which is located parallel with the rod 5, and is movable through a split clamp 24 connected to the lower portion of the cylinder 1, and said clamp is normally held in position to lock the rod 22 against movement by means of a piston 25 located in a cylinder 26. The cylinder 26 is located with its open end against one member 24^a of the clamp 24, and secured to the other member 24^b by means of bolts 27. The bolts 27 have heads 28 at one end, and are projected through openings 29 and 30 in the clamp members, and are screwed into threaded openings 31 in the integral ears 32 on the cylinder 26.

33 represents a fluid supply pipe which connects one end of the cylinder 26 with the top of valve casing 8, and is adapted to direct fluid to the cylinder 26, causing the piston 25 to move in one direction, and the cyl-

inder 26 to move in the other direction and move the members 24^a and 24^b toward each other to tightly grip the rod 23 and hold rod 5 against movement. The cylinder 26 and piston 25 therefore constitute a fluid lock which normally holds the parts against movement, and must be released before the rod 5 can operate. The passage of fluid to and from the cylinder 26 as well as the passage of fluid to and from the respective ends of the cylinder 1, is controlled entirely by my improved valve mechanism located in casing 8, and comprising two cylindrical members A and B of an external diameter 15 to fit within the cylindrical casing 8, and having their inner faces ground smooth so as to form a fluid cut off between them. Member B is provided centrally with an integral journal 34 projecting through a bearing sleeve 35 on casing 8, and provided at its outer end with a crank arm 36. This arm 36 is adapted to be manually operated and for the purpose I have shown a rod 37 which is pivotally connected to the crank 20 arm and extends to the engine cab or other convenient location for use, and it is to be understood that this rod 37 may be operated by any means desired. Member B on its inner face, at its center, is provided with a recessed bearing 38 in which a short arbor 39 integral with member A projects, so that the two members of the valve are held in proper relative position to each other regardless of the walls of the casing. Member 25 A has an integral journal 40 which projects through a stuffing box 41 in a removable plate 42 secured to the end of the casing. The journal 40 on its outer end is provided with a crank arm 43, and the latter is connected by a link 44 with the sliding block 19. It will therefore be noted that while member B is manually operated, member A is automatically operated by the block 19, and the latter is caused to move by the cam 45 bar 21, as the piston 6 and rod 5 are moved by the fluid pressure. Live fluid is supplied to an inlet port 45 in plate 42 by means of a supply pipe 46, and it will be noted particularly by reference to Figs. 5 and 8, that the outer face of valve member A is recessed forming a fluid chamber 47 back of said valve member. Valve member A is provided in its inner face at its upper portion with a recess 48, and through this recessed 50 portion 48, the valve member is provided with a V-shaped port 49 communicating at all times with the chamber 47. Around the port 49, valve member A is provided with a lap 50 flush with the surface of member A, so that the port 49 can extend from the periphery of the valve member an appreciable distance into the recessed portion 48 as it is to be understood that the lap 50 prevents any passage of fluid directly from 55 port 49 into recess 48. Valve member B is

provided in its periphery with a V-shaped port 51 of the same size, and normally registering with the port 49 in member A, and these ports 51 and 49 normally register with a duct 52 in casing 8. The pipe 33 above referred to for controlling the flow of fluid to the fluid lock communicates with this duct 52, so that the fluid lock is in normal operation. When member B is turned slightly in either direction, the port 51 will 70 be moved out of register with port 49, and the lap 50 will cut off the supply of live fluid to the fluid lock. As soon as the port 51 moves over the lap 50, the fluid in the pipe 33 will exhaust through the port 51 75 into recess 48 and from the recess 48 through an opening 55 in member B, and from the latter through an exhaust port 54 in casing 8, which latter discharges directly into the atmosphere. Valve member A is provided with two ports 56 and 57 respectively located at opposite sides of the member and separated by relatively narrow laps 58 from a groove 59, said groove being curved concentrically with the member and extending 80 from one lap 58 to the other. Valve member B is provided with two ports 60 and 61 respectively located at opposite sides of the valve, and adapted when the two valve members are located together to normally register with the respective ends of the groove 59, so that normally the ports 56 and 57 are 85 closed by the member B.

62 is an opening in member B which always connects groove 59 in member A with an exhaust port 63 in casing 8, so that the groove 59 is always in open communication with the atmosphere.

The ports 60 and 61 in member B are always maintained in communication with the 105 passages 9 and 10 in casing 8, the ends of said passages 9 and 10 in the inner face of the casing being sufficiently long to permit of this communication as shown clearly in the drawings.

110 The operation is as follows: When it is desired to move the rod 5 to the right of Fig. 1, member B is manually turned to the position shown in Fig. 7 where it will be noted that the port 51 connects the duct 52 115 with the recess 48 in member A, and as the latter communicates with opening 55 in member B, the pressure in the fluid lock will be released, and the rod 5 permitted to move. It will also be noted in Fig. 7, that 120 when the valve member B is moved to the position therein shown, that port 60 of member B registers with the port 56 of member A, and the live fluid will flow directly through such registering ports and 125 through the passage 9 to the left hand end of the cylinder, causing the piston 6 and rod 5 to move to the right of Fig. 1. It will also be noted that the port 61 connects passage 10 with the exhaust groove 59, so that 130

the fluid to the right of the piston 6 can be forced out through said port 61, groove 59, opening 62, and port 63. As the rod 5 is moved to the right of Fig. 1, the cam bar 21 will compel the block 19 and link 44 to move upwardly, thereby turning the member A, so that gradually the parts will be returned to their normal relative positions. While, of course, this normal relative position will be slightly different from the normal position above described, yet the valve members will have the same positions relative to each other, and the flow of live fluid to the ends of the cylinder will be cut off, and the flow of live fluid to the safety lock will be established so that the rod 5 will be securely held against movement. To reverse, the parts are moved in the opposite direction, and the operation above described is repeated so that while the valve members A and B control the flow of fluid to the cylinder and to the fluid lock, the movement of the rod 5 automatically returns the valve members to a position relative to each other to shut off the supply of fluid to the cylinder and establish the supply of fluid to the lock, and thereby automatically stop the rod and lock it at the proper position.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a reversing gear, the combination with a cylinder, a piston in the cylinder, and an operating rod connected to the piston and projecting through one end of the cylinder, of a fluid lock normally holding the rod against movement, a valve casing, a pipe connecting the valve casing with the fluid lock, said cylinder and valve casing having ducts therein connecting the valve casing with the opposite end of the cylinder, and a valve in said casing controlling the passage of fluid through the pipe and through said ducts, substantially as described.
2. In a reversing gear, the combination with a cylinder, a piston in the cylinder, and an operating rod connected to the piston and projecting through one end of the cylinder, of a fluid lock normally holding the rod against movement, and a two part valve controlling the flow of fluid to and from the member and the lock, substantially as described.
3. In a reversing gear, the combination with a cylinder, a piston in the cylinder, and an operating rod connected to the piston and projecting through one end of the cylinder, of a fluid lock normally holding the rod against movement, and a valve controlling the passage of fluid to and from the cylinder and to the fluid lock, substantially as described.
4. In a reversing gear, the combination with a cylinder, a piston in the cylinder, and an operating rod connected to the piston and projecting through one end of the cylinder, of a fluid lock normally holding the rod against movement, a valve casing, a pipe connecting the valve casing with the fluid lock, said cylinder and valve casing having ducts therein connecting the valve casing with the opposite end of the cylinder, and a valve in said casing controlling the passage of fluid through the pipe and through said ducts, substantially as described.
5. In a reversing gear, the combination with a cylinder, a piston in the cylinder, and an operating rod connected to the piston and projecting through one end of the cylinder, of a fluid lock normally holding the rod against movement, a valve casing, a pipe connecting the valve casing with the fluid lock, said cylinder and valve casing having ducts therein connecting the valve casing with the opposite end of the cylinder, and a valve in said casing controlling the passage of fluid through the pipe and through said ducts, substantially as described.
6. In a reversing gear, the combination with a cylinder, a piston in the cylinder, and an operating rod connected to the piston and projecting through one end of the cylinder, of a fluid lock normally holding the rod against movement, a valve controlling the passage of fluid to the cylinder and to the fluid lock, said valve comprising two members both movable relative to each other, substantially as described.
7. In a reversing gear, the combination with a cylinder, a piston in the cylinder, and an operating rod connected to the piston and projecting through one end of the cylinder, of a fluid lock normally holding the rod against movement, a valve controlling the passage of fluid to the cylinder and to the fluid lock, said valve comprising two members both movable relative to each other, one of said members constructed to be manually moved and the other of said members constructed to be automatically moved by the rod, substantially as described.
8. In a reversing gear, the combination with a cylinder, a piston in the cylinder, and an operating rod connected to the piston and projecting through one end of the cylinder, of a fluid lock normally holding the rod against movement, a valve casing, a pipe connecting the valve casing with the fluid lock, said cylinder and valve casing having ducts therein connecting the valve casing with the opposite end of the cylinder, and a valve in said casing controlling the passage of fluid through the pipe and through said ducts, substantially as described.

of said members constructed to be manually connected, and the other of said members constructed to be automatically moved by the rod, substantially as described.

- 5 9. In a reversing gear, the combination with a cylinder, a piston in the cylinder, and an operating rod connected to the piston and projecting through one end of the cylinder, of a fluid lock normally holding the rod against movement, a cam bar secured to and movable with the rod, a valve controlling the flow of fluid to the ends of the cylinder and to the fluid lock, means for manually operating the valve to admit fluid to either 10 end of the cylinder and to release the lock, and means operated by the cam bar to operate the valve to cut off the supply of fluid to the cylinder and compel the operation of the lock, substantially as described.
- 10 10. In a reversing gear, the combination with a cylinder, a piston in the cylinder, and an operating rod connected to the piston and projecting through one end of the cylinder, of a fluid lock normally holding the rod 15 against movement, a cam bar secured to and movable with the rod, a valve controlling the flow of fluid to the ends of the cylinder and to the fluid lock, means for manually operating the valve to admit fluid to either end of the cylinder and to release the lock, and means operated by the cam bar to operate the valve to cut off the supply of fluid to the cylinder and compel the operation of the lock, substantially as described.

- 20 11. In a reversing gear, the combination with a cylinder, a piston in the cylinder, and an operating rod connected to the piston and projecting through one end of the cylinder, of a fluid lock normally holding the rod 25 against movement, a cam bar secured to and movable with the rod, a valve comprising two members movable relative to each other, 30 one of said members constructed to be manually operated, and the other of said members constructed to be operated by the cam bar, substantially as described.

- 35 12. In a reversing gear, the combination with a cylinder, a piston in the cylinder, and an operating rod connected to the piston and projecting through one end of the cylinder, of a fluid lock normally holding the rod against movement, a cam bar secured to and 40 movable with the rod, a valve comprising two rotary members, journals fixed to said members and projecting through the casing, 45 a manually operated crank arm connected to one of said members, a crank arm connected to the other of said members, said last-mentioned crank arm constructed to be operated by the cam bar, substantially as described.

- 50 13. In a reversing gear, the combination with a cylinder, a piston in the cylinder, and an operating rod connected to the piston and projecting through one end of the cylinder, of a fluid lock normally holding the rod 55 against movement, a cam bar secured to and movable with the rod, a valve controlling the flow of fluid to the ends of the cylinder and to the fluid lock, means for manually operating the valve to admit fluid to either end of the cylinder and to release the lock, and means operated by the cam bar to operate the valve to cut off the supply of fluid to the cylinder and to the lock, substantially as described.

14. In a reversing gear, the combination with a cylinder, a piston in the cylinder, and an operating rod connected to the piston, and projecting through one end of the cylinder, of a fluid lock normally holding the rod against movement, a cylindrical valve 70 casing located adjacent the cylinder and having ports communicating with the opposite ends of the cylinder, a valve in said casing comprising two cylindrical members, means for manually turning one of said members, means for turning the other of said members by the movement of the rod, and said members having fluid passages therein 75 controlling the flow of fluid to the ends of the cylinder and to the lock, substantially as described.

15. In a reversing gear, the combination with a cylinder, a piston in the cylinder, and an operating rod connected to the piston, and projecting through one end of the cylinder, of a fluid lock normally holding the rod 80 against movement, a cylindrical valve 75 casing located adjacent the cylinder and having ports communicating with the opposite ends of the cylinder, a valve in said casing comprising two cylindrical members, means for manually turning one of said members, means for turning the other of said members by the movement of the rod, and said members having fluid passages therein 85 controlling the flow of fluid to the ends of the cylinder and to the lock, substantially as described.

16. In a reversing gear, the combination with a cylinder, a piston in the cylinder, and an operating rod connected to the piston, and projecting through one end of the cylinder, of a fluid lock normally holding the rod 90 against movement, a cylindrical valve 85 casing located adjacent the cylinder and having ports communicating with the opposite ends of the cylinder, a valve in 95 said casing comprising two cylindrical members, means for manually turning one of said members, means for turning the other of said members by the movement of the rod, means for admitting fluid to the valve 100 casing in rear of one of said members, both of said members having ports adapted to be moved into register to permit the flow of fluid to either end of the cylinder and to the fluid lock, and one of said members having 105 grooves therein adapted to register with openings in the other of said members, whereby the fluid from the ends of the casing and from the lock is permitted to exhaust through the valve, substantially as 110 described.

17. In a reversing gear, the combination with a cylinder, a piston in the cylinder, and an operating rod connected to the piston, and projecting through one end of the cylinder, of a fluid lock normally holding the rod 115 against movement, a cylindrical valve 105 casing located adjacent the cylinder and having ports communicating with the opposite ends of the cylinder, a valve in 120 said casing comprising two cylindrical members, means for manually turning one of said members, means for turning the other of said members by the movement of the rod, said members having fluid passages 125 therein controlling the flow of fluid to the ends of the cylinder and to the lock, journals on said members projecting through the casing, crank arms on the journals, manually operated means for moving one of the 130

crank arms, and automatic means moved by the rod for moving the other of said crank arms, substantially as described.

16. In a reversing gear, the combination with a cylinder, a piston in the cylinder, and an operating rod connected to the piston, and projecting through one end of the cylinder, of a fluid lock normally holding the rod against movement, a cylindrical valve casing located adjacent the cylinder and having ports communicating with the opposite ends of the cylinder, a valve in said casing comprising two cylindrical members, means for manually turning one of said members, means for turning the other of said members by the movement of the rod, means for admitting fluid to the valve casing in rear of one of said members, both of said members having ports adapted to be moved into register to permit the flow of fluid to either end of the cylinder and to the fluid lock, and one of said members having grooves therein adapted to register with openings in the other of said members, whereby the fluid from the ends of the casing and from the lock is permitted to exhaust through the valve, journals on said members projecting through the casing, crank arms on the journals, manually operated means for moving one of the crank arms, and automatic means moved by the rod for moving the other of said crank arms, substantially as described.

17. In a reversing gear, the combination with a cylinder, a piston in the cylinder, and an operating rod connected to the piston, and projecting through one end of the cylinder, of a fluid lock normally holding the rod against movement, a cylindrical valve casing located adjacent the cylinder and having ports communicating with the opposite ends of the cylinder, a valve in said casing comprising two cylindrical members, means for manually turning one of said members, means for turning the other of said members by the movement of the rod, and said members having fluid passages

therein controlling the flow of fluid to the ends of the cylinder and to the lock, one of said members having a central bearing 60 therein, the other of said members having a central arbor mounted to turn in the bearing, manually operated means for turning one of said members, and automatic operating means for turning the other of said 65 members, substantially as described.

18. In a reversing gear, the combination with a cylinder, a piston in the cylinder, and an operating rod connected to the piston, and projecting through one end of the cylinder, of a fluid lock normally holding the rod against movement, a cylindrical valve casing located adjacent the cylinder and having ports communicating with the opposite ends of the cylinder, a valve in said casing comprising two cylindrical members, means for manually turning one of said members, means for turning the other of said members by the movement of the rod, means for admitting fluid to the valve casing in rear of one of said members, both of said members having ports adapted to be moved into register to permit the flow of fluid to either end of the cylinder and to the fluid lock, and one of said members having 70 grooves therein adapted to register with openings in the other of said members, whereby the fluid from the ends of the casing and from the lock is permitted to exhaust through the valve, one of said members having a central bearing therein, the other of said members having a central arbor mounted to turn in the bearing, manually operated means for turning one of said members, and automatic operating means 75 for turning the other of said members, substantially as described.

In testimony whereof I have signed my name to this specification in the presence of two subscribing witnesses.

STEPHAN BAADER.
